CHARGING STAND FOR BATTERY OPERATED APPLIANCE

Donald A. De Varco, Elmhurst, Ill., assignor to Sunbeam
Corporation, Chicago, Ill., a corporation of Illinois

Filed July 12, 1968, Ser. No. 12,731

Term of patent 14 years

Int. Cl. D4—02

U.S. Cl. D4—16

FIG. 1 is a front perspective view of a charging stand for a battery operated appliance;

FIG. 2 is a top plan view thereof;

FIG. 3 is a side elevational view thereof; and

FIG. 4 is a rear elevational view thereof.

I claim:

The ornamental design for a charging stand for battery operated appliance, as shown.
